INSECT TRAP

Orest J. Hedgecock, Sr., 312 W. Homestead Ave.,
High Point, N.C.

Filed Jan. 29, 1960, Ser. No. 59,196

Term of patent 14 years

(Cl. D31—3)

Fig. 1

Fig. 2

FIG. 1 is a top perspective view showing the front of an insect trap embodying my new design;

FIG. 2 is a rear elevational view thereof; and

FIG. 3 is a top plan view thereof as shown in FIG. 2.

The bottom of the insect trap is flat and without ornamentation.

I claim:

The ornamental design for an insect trap, as shown and described.
